(57) **CLAIM**

The ornamental design for a portable information handling system housing, as shown and described.

DESCRIPTION

FIG. 1 is a front perspective view of a portable information handling system housing comprising the present invention; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof; FIG. 8 is a front perspective view in an open position thereof; FIG. 9 is another front view in an open position thereof; FIG. 10 is another rear view in an open position thereof; FIG. 11 is a left side view in an open position thereof; FIG. 12 is a right side view in an open position thereof; FIG. 13 is a top view in an open position thereof; FIG. 14 is a bottom view in an open position thereof; FIG. 15 is a front perspective view in a tablet position thereof; FIG. 16 is a front view in a tablet position thereof; FIG. 17 is a rear view in a tablet position thereof; FIG. 18 is a left side view in a tablet position thereof; FIG. 19 is a right side view in a tablet position thereof; FIG. 20 is a top view in a tablet position thereof; and, FIG. 21 is a bottom view in a tablet position thereof.

Broken lines shown in the drawings illustrate portions of the portable information handling system housing and form no part of the claimed design.
